UNITED STATES PATENT OFFICE.

JOSEPH GROSS, OF NEW YORK, N. Y.

SHOE-SHINING MACHINE.

Application filed January 4, 1924. Serial No. 684,381.

To all whom it may concern:

Be it known that I, JOSEPH GROSS, a citizen of the United States, residing at New York city, in the county of Bronx and 5 State of New York, have invented certain new and useful Improvements in Shoe-Shining Machines, of which the following is a specification, reference being had to the accompanying drawings.

10 This invention relates to certain improvements in shoe shining machines and it is an object of the invention to provide a device of this general character embodying novel and improved means whereby a shoe may be 15 polished through a series of mechanical operations and within a relatively short period of time.

It is also an object of the invention to provide a novel and improved device of this 20 general character embodying a member supported for reciprocatory movement and which member is provided with a polish applying means and with a polishing medium.

An additional object of the invention is 25 to provide a machine of this general character with a novel and improved means whereby a rubbing action may be imposed across the toe portion of the shoe to effect the desired highly polished finish.

30 The invention also has for an object to provide a novel and improved device of this general character which may be readily and conveniently adjusted for use in connection with shoes of various sizes and wherein the 35 various elements employed to effect the desired polishing of the shoe are arranged in proper sequence.

The invention consists in the details of 40 construction and in the combination and arrangement of the several parts of my improved shoe shining machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the 45 better understood, I will now proceed to describe the same with reference to the accompanying drawings, wherein:

Figure 1 is a view in top plan illustrating 50 a polishing machine constructed in accordance with an embodiment of my invention,

the top wall of the housing or cabinet being removed;

Figure 2 is a sectional view taken substantially on the line 2—2 of Figure 1, looking in the direction of the arrow; 60

Figure 3 is a sectional view taken substantially on the line 3—3 of Figure 1, looking in the direction of the arrow;

Figure 4 is a sectional view taken substantially on the line 4—4 of Figure 1; 65

Figure 5 is an elevational view of the adjusting member as herein employed unapplied;

Figure 6 is a fragmentary sectional view taken substantially on the line 6—6 of Figure 1; 70

Figure 7 is a fragmentary sectional view taken substantially on the line 7—7 of Figure 1.

As disclosed in the accompanying drawings, 75 C denotes a cabinet or housing of any preferred configuration and dimensions and in which is arranged the mechanism comprised in my improved shoe polishing machine.

The mechanism as herein disclosed comprises a shaft 1 supported for rotation by the side plates 2 and which is in driven connection, as at 3, with a motor M, preferably 80 of an electrical type. The operating circuit for the motor M may have imposed therein a check controlled circuit closer so that in order for the motor to operate it will be necessary to suitably deposit a coin of desired value, such as a nickel, and also 85 wherein after the depositing of the nickel the operating circuit for the motor is maintained closed for a predetermined period of time.

Each of the plates 2 is provided with an 90 elongated and horizontally disposed slot 4 through which is freely disposed an end portion of a rod 5. The rod 5 is adapted to be reciprocated within the slots 4 of the end plates 2 and as herein disclosed each 95 end portion of the rod 5 has operatively engaged therewith a pitman 6 also operatively engaged with a disc 7 fixed to the shaft 1, one of said discs 7 being comprised in the connection 3 hereinbefore referred to between the shaft 1 and the motor M.

Freely engaged with the shaft 1 is a bracket 8 provided with a forwardly extended bar 9, said bar 9 being of desired length and upon which is mounted a slide 10. The 100

slide 10 is fixed, as at 11, to the rod 5 hereinbefore referred to so that upon rotation of the shaft 1, the slide 10 will be reciprocated relative to the bar 9.

- 5 The slide 10 has arranged thereon a plate 12 of desired size and with which is adapted to be detachably or otherwise engaged a box 14. Arranged within the box 14 is a perforated partition or wall 15 arranged or
- 10 fashioned in close simulation to the toe or forward end portion of a shoe. This wall 15 is provided with a lining 16 of absorbent material which, when polish is applied thereto, readily transfers or applies such
- 15 polish to the toe portion of a shoe inserted within the box 14. The space between the wall 15 and the side walls of the box 14 is adapted to be filled with suitable shoe polish of desired color.
- 20 Also supported by the shaft 1 to one side of the bar 9 and in the same manner as such bar 9 is a second bar 17 with which is engaged a slide 18, said slide being also fixed to the rod 5 for reciprocation therewith.
- 25 The slide 18 has mounted thereon an abrading or rubbing member 19 also formed closely approaching the forward or toe portion of a shoe and which is adapted to rub such portion of the shoe after the application of the polish to create the initial or first shining operation.

Extending forwardly from the lower portions of the plates 2 are the strips or members 20 provided in their upper margins with the racks 21 meshing with the pinions 22 carried by the shaft 23. This shaft 23 is also disposed through the side frames 24, the lower portions of which being connected by the rods 25. The extremities of the rods 25 are inserted through the slots 26 provided with the members 20 whereby the frames 24 are supported for sliding movement toward or from the plates 2. The upper portions of the frames 24 at the forward portions thereof are connected by the vertically spaced bars 27 and 28, the upper bar 27 being provided with the heel supports 29 substantially aligned with the bars 9 and 17 hereinbefore referred to. The heel support 29 associated with the bar 9 or more particularly with the box 14 is provided at its forward portion with the box 30 substantially semi-circular in form adapted to contain the desired polish and the inner wall 30^a of said box is perforated and provided with an absorbent lining 31. When the heel of a shoe is placed upon this heel support 29, such heel portion will of necessity have rubbing contact with the lining 31, resulting in the proper application of the polish.

The shaft 23 extends exteriorly of the cabinet or housing C and is provided with an operating member 32. Upon proper rotation of the member 32 the frames 24 may

be adjusted toward or from the plates 2 to compensate for shoes of different sizes and if preferred an indicating means may be employed in connection with the shaft 23, said means being graduated in accordance 70 with the present sizing of foot wear.

The bars 27 and 28 at opposite sides of the second heel support 29 and in relatively close proximity thereto, rotatably support the vertically disposed shafts 33 extending 75 a desired distance above the upper bar 27. The shafts 33 are operatively connected by the gears 34 for unitary rotation but in opposite directions. The connection 34 as herein disclosed comprising two intermeshing gears of desired radii and extending outwardly from the hub of one of the gears is an elongated arm 35 which is freely disposed through the outer end portion of a bar 36 fixed to and extending forwardly 85 from the rod 5. As the rod 5 is moved back and forth, the coaction between the bar 36 and the arm 35 will result in desired oscillation of the shafts 33.

The shafts 33 above the bar 27 are provided with the rubbing or polishing heads 37, said heads being provided with the inwardly disposed rubbing or polishing flaps 38. When a shoe is in position to be acted upon by the member 19 and the heel rested 95 upon the second support 29, the heads 37 and the flaps 38 will serve to impart a shine to the heel portion of the shoe.

The shaft 1 is provided at the opposite side of the bar 17 with an upstanding bracket 39 to which is affixed a forwardly disposed bar 40, said bar also extending a slight distance rearwardly of the shaft 1. Depending from the opposite end portions of the bar 40 are the bearing arms 41 which 100 rotatably support the shaft 42 perpendicularly related to the shaft 1. The intermediate portion of the shaft 42 is operatively connected, as at 43, with a vertically disposed shaft 44 rotatably supported by the bar 40. The upper portion of the shaft 44 has fixed thereto a pinion 45 meshing with a rack bar 46. The rack bar 46 is carried by a slide 47, the forward end portion of which being fixed to an upstanding bracket 110 48 mounted upon the rod 5 while the opposite or rear end portion is freely disposed through a guide 49 carried by the shaft 1. As the rod 5 is moved back and forth within the slots 4 the shaft 42 will be intermittently rotated in opposite directions.

The rod 40 adjacent to its opposite ends is also provided with the upstanding bearing arms 50 which rotatably support a shaft 51 in parallelism with the shaft 42 and the forward end portions of the shafts 42 and 51 have fixed thereto the sprocket wheels 52 around which is disposed an endless sprocket chain 53.

Interposed between and connecting the 130

stretchers of the chain 53 and at points between the sprocket wheels 52 is a polishing or rubbing cloth 54. As the shaft 42 is operated, the resultant intermittent reverse travel of the chain 53 will cause the member 54 to have desired rubbing contact across the toe portion of the shoe to effect the finishing or high polish due to the fact that the toe of the shoe rested on the support 55 will displace or offset the intermediate portion of the member 54 resulting in the sliding or wiping action of said member 54 as it passes over the toe portion of the shoe. It is to be understood that the period of rotation of the shaft 42 in either direction will be insufficient to bring the extremities of the member 54 in interference with the sprockets 52. Supported upon the bar 27 forwardly of the bar 40 is a heel support 55. In the use of the machine, it is to be understood that a shoe is applied in sequence for the three operations required and the motor is adapted to run a sufficient period of time to effect the polishing of a pair of shoes.

My improved machine may be employed in public or in the household it being understood that when it is being employed for the latter purpose it is not operated under control of a coin.

From the foregoing description it is thought to be obvious that a shoe shining machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A shoe shining machine comprising, in combination, a member, means for supporting the same for reciprocatory movement, means for reciprocating the member, rubbing means for the forward end portion of a shoe carried by the member, movable means for rubbing the heel portion of the

shoe, and coacting means carried by the member and said last named rubbing means 55 for operating said last named rubbing means during reciprocation of the member.

2. A shoe shining machine comprising, in combination, a member, means for supporting the same for reciprocatory movement, 60 means for reciprocating the member, rubbing means for the forward end portion of a shoe carried by the member, movable means for rubbing the heel portion of the shoe, and coacting means carried by the member and 65 said last named rubbing means for operating said last named rubbing means during reciprocation of the member, said heel rubbing means being supported independently 70 of the reciprocating member.

3. A shoe shining machine comprising, in combination, a supporting structure, a heel support carried thereby, side plates mounted upon the supporting structure in advance 75 of the heel support, a shaft rotatably supported thereby, means for rotating the shaft, a bracket freely supported by the shaft and provided with a bar disposed in a direction toward the heel support, a slide mounted on the bracket, rubbing means carried by the 80 slide, and an operative connection between the slide and shaft for reciprocating the rubbing means toward or from the heel support upon rotation of the shaft.

4. A shoe shining machine comprising, in 85 combination, a supporting structure, a heel support carried thereby, side plates mounted upon the supporting structure in advance of the heel support, a shaft rotatably supported thereby, means for rotating the shaft, 90 a bracket freely supported by the shaft and provided with a bar disposed in a direction toward the heel support, a slide mounted on the bracket, rubbing means carried by the 95 slide, an operative connection between the slide and shaft for reciprocating the rubbing means toward or from the heel support upon rotation of the shaft, a rotatable rubbing member including an outstanding operating bar, and an operative connection between the bar and slide for oscillating the bar upon reciprocation of the slide to operate the rotatable rubbing member.

In testimony whereof I hereunto affix my signature.

JOSEPH GROSS.
